[57] **CLAIM**

The ornamental design for a latch for snips, as shown and described.

DESCRIPTION

FIG. 1 is a left-front perspective view of the latch for snips showing my new design;

FIG. 2 is a front elevational view thereof;

FIG. 3 is a rear elevational view thereof;

FIG. 4 is a top plan view thereof;

FIG. 5 is a right side elevational view thereof;

FIG. 6 is a left side elevational view thereof;

FIG. 7 is a bottom plan view thereof;

FIG. 8 is a left side elevational view thereof, shown on a reduced scale; and,

FIG. 9 is a cross-sectional view taken along line 9—9 in FIG. 8.

The broken line portions of the drawing are for illustrative purposes only and form no part of the claimed design.
